FOOD COOKING GRILL

Edward M. Marshall, 8107 SW. 72nd Ave., Apt. 102 E,
Miami, Fla. 33143

Filed Nov. 16, 1970, Ser. No. 26,033

Term of patent 3½ years

Int. Cl. D07—02

U.S. Cl. D81—10

FIG. 1

FIG. 2

FIG. 3

FIG. 4

FIG. 5

FIG. 1 is a front elevational view of a food cooking grill showing my new design, one cover being in open position.

FIG. 2 is a top plan view thereof.

FIG. 3 is a right hand end elevational view thereof.

FIG. 4 is a rear elevational view thereof.

FIG. 5 is a left hand end elevational view thereof.

I claim:

The ornamental design for a food cooking grill, as shown and described.
